UNITED STATES PATENT OFFICE.

LAURENCE V. BENÉT AND HENRI A. MERCIÉ, OF PARIS, FRANCE, AS-SIGNORS TO THE HOTCHKISS ORDNANCE COMPANY, LIMITED, OF LONDON, ENGLAND.

CARTRIDGE-FEED BELT.

SPECIFICATION forming part of Letters Patent No. 595,518, dated December 14, 1897.

Application filed September 7, 1897. Serial No. 650,833. (No model.)

To all whom it may concern:

Be it known that we, LAURENCE V. BENÉT, a citizen of the United States, and HENRI A. MERCIÉ, a citizen of the Republic of France, both residing at Paris, in the Republic of France, have invented a new and useful Improvement in Cartridge-Carrying Belts Used in Feeding Automatic Machine-Guns with Cartridges, of which the following is a specification.

The present invention relates to cartridge-carrying belts used in feeding automatic machine-guns, and more particularly to that kind of belt described in our former Letters Patent, dated July 14, 1896, No. 564,043. As distinguished from the feed-strip described in the said patent, the belt constructed in accordance with the present improvements is neither formed of a single straight piece of metal of limited length and more or less elastic, as shown in Figure 64 of the said patent, nor of a series of individually-formed cartridge-carriers which are linked more or less flexibly together, as shown in Fig. 67 of the said patent, but is formed of individual cartridge-carriers of an improved construction, which are slipped or threaded onto one or more longitudinal bands or ribbons of metal for uniting the carriers together side by side into a flexible belt.

A feed-belt constructed in accordance with the present improvements affords the advantage of being highly flexible without presenting any risk of tearing the carriers apart, as is likely to be the case with the feed-belt shown in Fig. 67 of the said patent, particularly if it be considered that the feed strip or belt is pulled through the automatic machine-gun with considerable violence. Moreover, a feed-belt as herein constructed enables of its being readily utilized in the form of a coil of long dimensions capable of being wound in a drum placed alongside of the gun. Furthermore, the individual carriers as herein constructed are strong and capable of readily resisting the wear and tear they are subjected to by the device operating in the gun for feeding the cartridge-carrying belt or strip therethrough.

The improved construction of cartridge-carrying belt is particularly intended to be used with the well-known Hotchkiss automatic machine-gun; but it is obvious that it is capable of being used with any other kind of machine-gun.

In the accompanying drawings we have shown the various phases for the manufacture of this improved cartridge-carrying feed-belt, as well as the completed belt itself, all in full size.

Fig. 1 is a plan showing a portion of the completed belt, comprising four cartridge-carriers. Fig. 2 is a section on the line 2 2 of Fig. 1, looking in the direction of the arrows. Fig. 3 is a section on the broken line 3 3 of Fig. 1, looking in the direction of the arrows. Figs. 4, 5, and 6 are plans, and Figs. 7 to 14 are perspective views, showing the successive phases of manufacture. Figs. 15 and 16 show an improved tongue for facilitating the introduction of the feed-belt into the machine-gun.

A blank 1 assuming the shape shown in Fig. 4 is first produced, after which two slots 2 2 are punched out, Fig. 5, nicks are made at 3 3 3 3, and incisions at 4 4, Fig. 6. The clips 5, 6, and 7, by means of which the cartridge is to be held, are then bent over, as in Fig. 7, and the lips 8, 9, 10, 11, 12, and 13 are bent down, as in Fig. 8, whereupon the blank 80 itself is bent into the position shown in Fig. 9 and then into the position shown in Fig. 10, after which it is ready to be slipped onto two long metallic bands or ribbons 14 15, as shown in Fig. 11. When the blank has 85 reached that stage of manufacture, the lips 8, 9, 12, and 13 are bent over against the body of the blank 1 and the lips 10 11 are likewise bent down in such a manner as to cause them to enter the slots 2 2, as shown in Fig. 12, 90 after which a lip 16 is bent up against the clip 6 and acts to reinforce the clip 6, against which operates the feed-wheel or other actuating device of the machine-gun for feeding the cartridge-carrying belt through the 95 mechanism of the gun, as will be readily understood on referring to our said prior patent.

The cartridge-carrier is now completed and

only requires to be securely attached to the bands 14 15. This is accomplished as regards the band 14 by producing a depression at 17, Figs. 1 and 2, so as to disturb the three thicknesses of metal and unite them firmly, and as regards the band 15 by punching the three thicknesses through at 18 to form a projection 19, against which rests the head of the cartridge 20, as shown in Fig. 1.

10 In Figs. 15 and 16 we have shown in plan and elevation an improved tongue on the end of the belt, the said tongue acting to facilitate the introduction of the belt into the machine-gun.

15 The band 15 is extended a short distance beyond the first cartridge-carrier 1 of the series on the belt, and to the said extension is fastened, by means of a covering-plate 21 and rivets or screws 22, a band of leather, soft 20 rubber, canvas, or other suitable flexible material 23, having a tapered tip 24 of metal or other suitable substance.

What we claim as new, and desire to secure by Letters Patent, is—

25 1. A cartridge-carrier formed of a blank, bent over upon itself at the ends and secured together, and having clips to hold the cartridge, substantially as described.

2. A cartridge-carrier formed of a blank 30 having clips to hold the cartridge, and lips at the ends thereof, the said blank being bent over upon itself near the ends, and the said lips bent over the central portion of the blank to hold the ends down, substantially as de- 35 scribed.

3. A cartridge-carrier formed of a blank having clips to hold the cartridge, lips at and near the ends thereof, and slots in the central portion; the said blank being bent over 40 upon itself near the ends, and the said lips being bent over the edges of the central portion of the blank, and two of the lips entering the said slots to hold the ends down, substan- tially as described.

4. A cartridge-carrier formed of a blank having clips to hold the cartridge, and lips at and near the ends thereof, the said blank being bent over upon itself near the ends, and the said lips being bent over the edges 50 of the central portion of the blank to hold the ends down, and one of the said lips being bent up against one of the said clips to reinforce the same, substantially as described.

5. In a feed-belt for automatic machine- 55 guns, the combination with two bands; of cartridge-carriers formed of blanks bent over upon themselves and secured together, and having clips to hold the cartridge; the said cartridge-carriers being placed upon the said bands, and means for securing the carriers to the said bands, substantially as described.

6. In a feed-belt for automatic machine- 65 guns, the combination with two bands; of cartridge-carriers formed of blanks having clips to hold the cartridges and lips near the ends thereof; the said blanks being bent over upon themselves and the said lips bent over the

central portion thereof; the said carriers being placed upon the said bands; and means for securing the said carriers to the said bands, sub- 70 stantially as described.

7. In a feed-band for automatic machine-guns, the combination with two bands; of cartridge-carriers formed of blanks having clips to hold the cartridges and lips near the ends 75 thereof; the said blanks being bent over upon themselves and the said lips bent over the central portion thereof; one of the said lips being bent against one of the clips to reinforce the same; the said carriers being placed upon 80 the said bands and means for securing the said carriers to the said bands, substantially as described.

8. In a feed-band for automatic machine-guns, the combination with two bands; of cartridge-carriers formed of blanks having clips to hold the cartridges and lips near the ends 85 thereof; the said blanks being bent over upon themselves and the said lips bent over the central part thereof; the said carriers being 90 placed upon the said bands; means for securing the said carriers to the said bands, and a lug 19 formed on the carriers, substantially as described.

9. In a feed-band for automatic machine- 95 guns, the combination with two bands; of cartridge-carriers formed of blanks having clips to hold the cartridges and lips near the ends thereof; the said blanks being bent over upon themselves and the said lips bent over the 100 central part thereof; the said carriers being placed upon the said bands; means for securing the said carriers to the said bands, and a flexible band 23 secured to the said belt, sub- 105 stantially as described.

10. A feed-belt for automatic machine-guns, consisting of two bands; distinct cartridge-carriers secured to the said bands; each of said carriers being formed of a blank doubled over upon itself, and having clips to 110 hold the cartridges; and a lip laid against one of the said clips for reinforcing the latter, substantially as described.

11. A feed-belt for automatic machine- 115 guns, consisting of two bands; distinct cartridge-carriers secured to the said bands; each of said carriers being formed of a blank doubled over upon itself, and having clips on the central portion to hold the cartridge, and slots also in the central portion and lips on the 120 bent-over portions to engage the said slots, substantially as described.

12. A feed-belt for automatic machine- 125 guns, consisting of two bands; distinct cartridge-carriers secured to the said bands; each of said carriers being formed of a blank doubled over upon itself, and having clips on the central portion to hold the cartridge; and lips on the bent-over portion to engage the 130 central portion, one of the said lips being laid against one of the said clips, substantially as described.

13. A feed-belt for automatic machine- guns, consisting of two bands; distinct car-

tridge-carriers secured to the said bands; each of said carriers being formed of a blank doubled over upon itself, and having clips to hold the cartridges; a lip laid against one of the said clips, and a flexible band 23 secured to one end of the belt, substantially as described.

In witness whereof we have hereunto set

our hands, this 26th day of August, 1897, in presence of two subscribing witnesses.
